UNITED STATES PATENT OFFICE.

HENRY L. CHARLES, OF KENT, WASHINGTON.

SMELTING FURNACE.

Application filed December 29, 1925. Serial No. 78,155.

My invention relates to improvements in smelting furnaces of the reverberatory type, and includes instrumentalities which make it particularly useful relative to furnaces of 5 large capacity.

Heretofore, in the building of furnaces of this class, the common practice has been to provide a horizontally disposed silica hearth, and in the operation of the same to maintain 10 therein a wide bath of metal, this latter procedure requiring in many instances the tying up of a large amount of capital in metal.

In the interests of economy and facility of operation, I provide, as the objects of my 15 invention:

A silica bottom having integral therewith a longitudinally extending central mound, and, also integral with said bottom, a convexly shaped bank extending along each side 20 and end of the furnace, the mound and banks while forming the hearth and performing the functions of the same yet serving to take the place of metal which would otherwise be tied up. Said banks also subserve the purpose of protecting the sides of 25 the furnace, and permit, by reason of their form, ready repairs for corrosion, as will be hereinafter more particularly described.

Other objects will appear as the description of the invention progresses.

In the accompanying drawings—

Figure 1 is a cross section of the furnace drawn on the line 1—1, of Fig. 2;

Fig. 2, a plan view of the same, broken away, the firing end being indicated, but the flue end omitted; and,

Fig. 3, a longitudinal section through the line 3—3, of Fig. 2.

The base of the structure 1, constructed of 40 concrete in the customary manner, supports vertically extending and parallel side walls 2, a wall 3, representing the firing end, a flue end, which is of ordinary construction and hence not shown, and an arched roof 45 generally designated as 4.

The hearth, built up of silicious material, 50 consists of an integral banked section 5, convex in form, extending along each side and end of the furnace, and having its upper 55 terminal near the arch; in other words, the hearth is brought up adjacent the roof. A longitudinally extending mound portion 6, integral with the banked section at the firing end and the lowermost sections of the 60 hearth, divides the smelting zone of the hearth into two parts. This mound is de-

signed to extend for about two-thirds of the length of the furnace, and it is provided at its free end with a pointed terminal 7. 8 and 9 denote the lowermost sections of the 60 hearth, disposed between the mound and the banked sections; 8, as it will be noted in Fig. 1, being inclined and slightly higher than the section 9. This inclined section and the pointed terminal of the mound are 65 for the purpose of facilitating the flow of the metal into the metal bath 10 and out through the tap hole 11. The matte and slag lines, designated by 12 and 13 in Fig. 1, show where these lines should be most 70 effectively located when the furnace is operating under usual conditions, the matte covering the mound so as to limit, if not preclude, corrosion taking place therein.

The centrally located hoppers 20 and 75 the side hoppers 21 are designed to be of the usual construction. The means for firing the furnace 22, and the buckstaves and connections, generally designated as 23, are also of ordinary construction, and perform 80 their common functions.

In operating the furnace, the charges are fed principally through the three central hoppers upon deep accumulations of the molten material. Corrosion in the sides of 85 the hearth will take place particularly at the points where the slag and matte lines meet, causing, by reason of the bulging contours of the sides, the formation therein of convenient recesses for the reception of fettling 90 material. The two hoppers, located adjacent the sides and directly above these points, are designed primarily for the purpose of feeding such material to the sides. This material may include magnesite, either 95 ground or in other suitable form, chromite, or ground magnesite brick bats corroded with a basic slag, such as can be reclaimed out of the tuyères of a converter. Obviously, the thick embankments afford more protection to the sides of the furnace than that usually provided, and their convex form makes the application of the repair material more easy and effective than where the sides of the furnace present inverted or angularly disposed sections, incident to the ordinary construction, or side feeding.

The utilization of large furnaces of this class, entails the tying up of large sums of 110 money in metal in order to maintain the molten material at the proper level and confine the corrosive action of the smelting op-

eration to definite areas of the furnace. The central mound portion is designed to take the place of metal which would otherwise be tied up, and in dividing the smelting zone, as it does, deep masses of the molten material are attained, having comparatively wide receptive surfaces for the charges to fall upon, and at the same time said material is brought relatively close to the arch, with the result that the charges are subjected to an intense radiant heat from the arch itself, as well as the extra heat generated by the deep masses of the material.

This construction also makes possible the use of the furnace in smelting ores of different kinds, as, for instance, one side may be used for treating gold and silver ores, and the other side used only for the treatment of ores of copper, lead, iron or zinc; that is to say, a very stubborn or hard smelting ore may be treated on one side and an easily smelted ore treated on the other side. Further, to make the furnace practically indestructible, the alternate feeding of the hard smelting or refractory ores from one side to the other may be employed, which will effectively prevent injurious corrosion of the sides at all. Another useful result is also obtained, in that one side may be kept full of ore at all times, while the other side is kept in molten condition, the ore receiving indirectly the benefit of the heating treatment directed to the other side and being adapted to be more quickly acted upon by the flames when subjected thereto.

As will be obvious to those skilled in the art, changes in and modifications of the construction described may be made without departing from the spirit of my invention or sacrificing its advantages.

I claim:

1. In a smelting furnace having vertically extending side and end walls, a roof, a firing end and a flue end, a hearth provided with a convexly shaped integral bank extending along each side and end wall and terminating adjacent the roof, and a longitudinally extending and integral mound disposed in spaced relation between the

banks at the side walls, one end of the mound being contiguous with the bank at the firing end, and the other end semiconical in form and spaced away from the bank at the flue end.

2. In a smelting furnace having vertically extending side and end walls, a roof and a tap hole, a hearth provided with a thick convexly shaped integral bank extending along each side and end wall and terminating adjacent the roof, and a longitudinally extending and integral mound disposed in spaced relation between the side banks, one end of the mound being contiguous with the bank at one end wall, and the other end reduced in size and terminating adjacent the tap hole.

3. In a smelting furnace having side walls, a firing end, a flue end and a roof, a hearth, disposed in the bottom of the furnace, provided with an inwardly bulging bank extending contiguously with said walls and ends and terminating adjacent the roof, and a longitudinally extending mound disposed in spaced relation with the side walls, said mound being contiguous with the firing end and terminating short of the flue end.

4. In a smelting furnace having a hearth disposed in the bottom thereof, a mound, integral with the hearth, adapted to partition the smelting zone of the hearth and displace charges of ores, and molten material, during the smelting operation, and whereby the depth of the bath is materially increased.

5. In a furnace for smelting ores having side walls, a firing end, a flue end, and a hearth disposed in the bottom of the furnace, a longitudinally extending mound contiguous with the firing end and terminating short of the flue end, said mound being spaced away from the side walls.

6. In a furnace for smelting ores having a hearth located in the bottom thereof, a mound disposed centrally of the hearth, adapted to displace charges of ores, and molten material, during the smelting operation, and increase the depth of the bath without reducing its upper smelting area.

HENRY L. CHARLES.
